UNITED STATES PATENT OFFICE

VICTOR R. DESPARD AND HANS C. R. POPP, OF VALPARAISO, INDIANA, ASSIGNEES TO
MCGILL MANUFACTURING COMPANY, A CORPORATION OF INDIANA

ELECTRIC-LIGHT CLUSTER

Application filed June 10, 1927. Serial No. 197,944.

Our invention relates to electric light clusters wherein a plurality of lamp sockets are supported from a central hollow body. In such clusters it has heretofore been the practice to secure the lamp sockets to the body by means of hollow members through which the wires for the sockets extend. To connect these clusters to a source of current it is necessary to extend the wires through the hollow stem upon which the body is mounted and then divide the conductors and thread one portion of each through the hollow members and connect the portions to the lamp sockets. To properly connect the wires to the sockets requires considerable skill and time. Then if the sockets are adjustable relative to the body the adjustment of the sockets from one position to another must of course twist the wires and often causes them to become loosened.

It is a purpose of this invention to provide a cluster in which these difficulties of wiring are eliminated. This is accomplished by the utilization of a socket to body connection with means secured in the body cooperating with the sockets and having only two points of connection for the lead in wires to connect the sockets to the source of current supply.

It is also a purpose of this invention to so mount the sockets with respect to the supporting body that they may be rotated relative thereto without twisting or moving the connecting wires or endangering the socket connections to the source of current.

A further purpose of this invention is to so mount the hollow body and the connections between the lamp sockets carried thereby and the source of current that the connections are held in proper position to engage the terminals of the lamp sockets at all times.

Other objects and advantages will appear as the description proceeds in connection with the accompanying drawings wherein the preferred form of the invention is shown. It is obvious however, that various changes may be made in the details of construction without departing from the spirit of the invention and we wish it to be understood that we intend to avail ourselves of all such modi-

fications as fall within the scope of the claims.

In the drawings:

Fig. 1 is a side view of the improved cluster with part of the hollow supporting body 55 broken away to show the switch operating mechanism;

Fig. 2 is a sectional view taken vertically through the structure along the line 2—2 of Fig. 3;

Fig. 3 is a horizontal sectional view taken on the line 3—3 of Fig. 2;

Fig. 4 is a vertical sectional view taken on the line 4—4 of Fig. 1;

Fig. 5 is a vertical section substantially on the line 5—5 of Fig. 2;

Fig. 6 is a detailed view of the switch mechanism showing the arrangement of the stationary and movable contacts;

Fig. 7 is a section on the line 7—7 of Fig. 6;

Fig. 8 is a detailed perspective view of one of the terminals for the lamp sockets;

Fig. 9 is a perspective view showing the connector elements detached from the supporting insulating block which carries them;

Fig. 10 is a perspective view of the supporting insulating block; and

Fig. 11 is a perspective view of the screw socket used to receive the lamp, with one of the terminals therefor.

Referring now in detail to the drawings the improved lamp cluster consists primarily of a supporting stem 15 through which the conductors from the source of current are extended into the hollow portion 16 mounted 85 thereon, the hollow body portion 16 and a pair of lamp sockets 17 and 18 together with the means shown at 19 in Fig. 1 for supporting a shade over the cluster.

The hollow support 15 as shown more 90 clearly in Fig. 2 consists of the outer tubular member 20 and the inner conduit 21 through which the conductors 22 extend. The members 20 and 21 may be connected together in any suitable manner so that the member 21 95 projects upwardly slightly above the outer sleeve 20 and is screw threaded at its upper end as shown at 23. The hollow body 16 which is substantially spherical and consists of a pair of semi-spherical parts 24 and 25 100

is adapted to be supported and secured upon the members 20 and 21. As shown, the member 24 forming the lower half of the hollow body is pressed inwardly at its bottom as at 25 to provide an annular seat or shoulder resting on top of the sleeve 20 and fitting down over the screw threaded end 23 of the conduit 21.

Struck up from the rim of this annular shoulder portion 25 are a pair of projections 26 and 27 which fit in slots 28 and 29 provided in the horizontally extending portion 30 of the supporting member 31 which, as shown clearly in Figs. 2 and 4, is screw threaded to engage the screw threads 23 on the conduit 21. Thus, by screwing the supporting member 31 down upon the conduit 21, the lower half 24 of the hollow supporting body will be locked into position thereon and will be held against rotation relative to the member 31 by means of the projections 26 and 27 and the slots 28 and 29. The supporting member 31 is provided at its upper end with horizontal portion 32 screw threaded to receive the screw threaded member 33 and the upper half 25 of the hollow body portion is provided with an inward depression as shown at 34 and this depression is provided with an opening through which the member 33 extends.

In order to clamp the upper half 25, which is outwardly flanged as shown in Fig. 4 to fit over the lower half 24, down upon the lower half 24, I provide a screw threaded member 35 fitting into the depression 34 whereby it may be screwed down upon the member 33 to secure the hollow portion 25 in position. The member 35 is also provided with a shoulder at 36 to receive the sleeve 37 and resting upon this sleeve 37 is a flat disc like member 38 which is also screw threaded upon the member 33 to provide a flat support to receive a lamp shade which may be held in position by the finishing knob 39.

The hollow body portion 16 is provided with a pair of openings at opposite sides thereof to receive the lamp sockets 17 and 18 which, as shown, have the housings 40 and 41 of insulating material provided with the projections 42 and 43 extending at right angles to the sockets and having flanges 44 and 45 rounded to fit the spherical inner surface of the member 16 around the openings provided therein. This provides a very simple and substantial means for connecting the sockets to the hollow body since it eliminates all extra eyelet or tube parts which have heretofore been used in connecting the lamp sockets to the hollow body. The extensions 42 and 43 together with their flanges 44 and 45 also serve to swivelly connect the lamp sockets to the hollow body portion.

Each lamp socket consists of the screw threaded hollow member 48 which is adapted to receive the screw threaded end of the lamp

bulb and the connecting member 49 which serves as a contact for the end of the lamp bulb, this member 49 being in the form of a rivet and being insulated from the member 48 by means of the disc 50 which engages the end portion 51 of the screw threaded member 48 and holds it in place within the insulating body when the rivet 49 is extended therethrough and upset as at 52 in the depression 53 provided in the lamp socket. The rivet 49 also clamps the terminal 55 to the insulating body and is directly connected thereto so as to make an electric connection with the terminal 55. This terminal as shown extends laterally through the slot 56 provided in the member 48 and is prevented from engaging with the member 48 by the downwardly extending ribs 57 and 58 provided on the insulating body on opposite sides of the thin portion 59 of the terminal 55. This terminal then extends through an opening provided in the extension 42 and is provided with a downturned end at 60 which is substantially flush with the inner face of the extension and substantially centrally located with respect to the opening in the hollow body receiving the extension 42. This provides a central terminal for the lamp socket which terminates within the hollow body portion for a purpose which will presently appear.

To provide for the other terminal of the lamp socket, a portion 61 is struck out of the screw threaded member at its side and a rivet 62 connects the struck out portion 61 with the terminal 63 through the slot defined by the projections 64 and 65 extending into the opening through the extension 42. The terminal 63 as shown fits in a recess provided on the inner face of the extension 42 and is in the form of a circular ring portion 66 surrounding the centrally located terminal 60. This description has been made particularly with reference to the left hand socket shown in Fig. 2 and it is obvious that the right hand socket is simply a duplicate thereof and it is thought no further description need be made of it. The two lamp sockets are directly opposite each other and as shown in Fig. 2 align substantially with the projections 26 and 27 which lock the hollow body portion against rotation relative to the support 31. This support carries means for connecting the terminals of the lamp sockets to the conductors for supplying current in such a manner that regardless of the position the sockets are moved to, the terminals are always connected so that the lamps may be lighted. This connecting means consists of an insulating connecting block 70 which is secured by means of the screw 71 to the supporting member 31 and is provided at its top as shown in Figs. 2 and 5 with a pair of terminals 72 and 73 to which the conductors from the source of current are connected. The terminal 72 connects to the member 74 which, as shown in Figs. 130

9 and 10, is adapted to fit in the slot 75 and has a flat face 76 for a purpose which will presently appear.

Extending from the terminal 73 is a connecting bar 77 which fits in the slot 78 provided in the insulating block 70 and extends downwardly and rearwardly as at 79 where it is provided with the long narrow portion 80 fitting in a deep slot at 81 within the block 70 and is then provided at its lower end with the outwardly projecting flat portion 82 against which the spring 83 bears. This spring 83 engages at its other end with a sliding contact 84 which slides in the slot 85 provided in the block 70 and is adapted to contact with the annular portion 66 of contact 63 on the lamp socket 17. Directly opposite the contact member 84 is a similar contact member 86 sliding in the slot 87 in the block 70 and pressed toward outward position and into engagement with the annular terminal on the socket 18 by means of the spring 88. The springs 83 and 88 it will be noted are insulated from each other by the partition wall 89 formed in the block 70.

Contact is made with the two central terminals of the sockets 17 and 18 by means of the members 90 and 91 fitting upon the projections 92 and 93 and having an inturned portion fitting within the slots provided in the connecting block on opposite sides of the projections 92 and 93. The members 90 and 91 have downturned adjacent end portions shown at 94 and 95 which are connected by means of the spring 96 lying in the slot provided in the connecting block between the portions 92 and 93, this slot being of less depth than the slot 81 so that the spring is held out of contact with the portion 80 of the bar 77, the spring member 96 in this case serving to yieldingly press the contacts 90 and 91 into engagement with their respective terminals on the sockets 17 and 18. The contact 91 is also provided with an upwardly projecting portion 98 for a purpose which will presently appear.

The connecting block 70 also supports a switch indicated generally by the numeral 100 by means of a pair of screws 101 and 102 which extend from the connecting block through slots provided in the members 90 and 91 and through the insulating plate 103 fitting over the connecting block and thence through the switch to the outer face 104 thereof. This switch is provided with four contact members 105 and 106, 107, and 108 which contact respectively with the portion 74 connected to the terminal 72, projection 98 on the contact 91, contact 86 and contact 84 as indicated in dotted lines in Fig. 2. These contact members as shown in Figs. 6 and 7 extend from the terminals 109, 110, 111, and 112 of the stationary contact for the switch member 105 and extend through the insulating body of

the switch into engagement with the respective members on the contact block.

The details of this switch are similar to that shown in the application of Victor Despard, Serial No. 62833, now Patent No. 1,669,372 filed October 16, 1925 on multiple series switch and serves to connect the lamp sockets 17 and 18 with the terminals 72 and 73 through the terminals provided on the lamp sockets and the block 70 either in series or parallel or to wholly disconnect the lamp sockets from the source of current. The structural details of this switch since they form no part of the present invention will therefore not be further described except in so far as is necessary to bring out the cooperation between the switch structure and the lamp cluster.

The operating stem 120 of the switch as shown clearly in Figs. 1 and 3 connects to a ratchet wheel 121 by means of the prongs 122 and 123 and is operated by means of the lever 124 and the spring 125 so as to cause a step by step rotation of the wheel 121 and the stem 120 to establish various connections between the terminals 72 and 73 in the lamp sockets. A pull chain 125 is connected to the lever 124 and extends outwardly through an opening 126 in the hollow body 16 for operating the switch.

From the above description it is thought that the construction and operation of this device will be clear to those skilled in this art and the advantages will be clearly apparent. The provision of the connecting block mounted on the supporting member 31 together with the terminals on the lamp sockets extending into the hollow body 16 and engaging with the terminals on the connecting blocks 70 eliminates the undesirable features in wiring which have heretofore been present in lamp clusters since the conductors extending up through the support need only to be connected to the terminals 72 and 73 before the cap portion 25 is placed on the lower half 24 of the hollow body to complete the wiring of the device. The lamp sockets provided are compact and simple in structure and when set in position on the hollow body they are permanently connected by means of the terminals fixed thereon to the spring pressed contacts on the connecting block and remain so connected even though they are rotated with respect to the body portion. The spring pressed contacts in addition serve to press the flanges 44 and 45 outwardly against the hollow body and yieldingly hold the lamp sockets in any position to which they are adjusted.

Having thus described our invention what we claim and desire to secure by Letters Patent of the United States is:

- An electric lamp cluster comprising a hollow body, a plurality of lamp sockets extending substantially tangentially of said body and, having portions of insulating ma-

- aterial at one side thereof extending into said body for supporting said sockets, and terminals for said sockets extending into said body through said portions.
2. An electric lamp cluster comprising a hollow body, a plurality of lamp sockets extending substantially tangentially of said body and, having portions of insulating material at one side thereof extending into said body for supporting said sockets, and terminals for said sockets extending toward said body through said portions, said portions being rockably connected to said body.
3. An electric lamp cluster comprising a hollow body, a plurality of lamp sockets having portions of insulating material projecting from one side thereof extending into said body for supporting said sockets, and terminals rigidly secured to said sockets and extending toward said body through said portions.
4. An electric lamp cluster comprising a hollow body, a plurality of lamp sockets having portions projecting at right angles to the axes of said sockets swivelly connected to said body, terminals secured to said sockets and extending into said body, a support within said body, contacts carried by said support and engaging said terminals, and means for connecting said contacts to a source of current supply.
5. An electric lamp cluster comprising a hollow body, a plurality of lamp sockets having portions of insulating material extending to right angles to the axes of said sockets and into said body for supporting said sockets, terminals for said sockets extending into said body through said portions, a support within said body, contacts on said support engaging said terminals and means for connecting said contacts to a source of current supply.
6. An electric lamp cluster including a conductor containing support, a hollow body, a supporting member within said body having means thereon engaging said support to secure the hollow body thereon, and interlocking means on said body and member preventing rotation of said member relative to said body, lamp sockets projecting from said body, contacts carried by said member and electrically and slidably connected to said sockets and means on said member for connecting said contacts to conductors extending from said support into said body.
7. An electric lamp cluster including a conductor containing support, a hollow body, a supporting member within said body having means thereon engaging said support to secure the hollow body thereon, and interengaging means on said body and member preventing rotation of said member relative to said body, lamp sockets supported on said body and having terminals extending into said body, and contacts carried by said member en-
- gaging said terminals, said interengaging means retaining said contacts and terminals in alignment.
8. A lamp cluster comprising two lamp sockets, attaching means for said sockets secured to and projecting laterally from the sides thereof, and a support for said sockets made in two parts said parts having complementary means for engaging said attaching means and holding said sockets in position upon said support.
- In witness whereof, we hereunto subscribe our names this 16th day of May, A. D. 1927.
- VICTOR R. DESPARD.
HANS C. R. POPP.
